ELECTRIC SWITCH

Filed March 2, 1923

2 Sheets-Sheet 2

UNITED STATES PATENT OFFICE.

HERMAN J. H. HUBER, OF SCHENECTADY, NEW YORK, ASSIGNOR TO GENERAL ELECTRIC COMPANY, A CORPORATION OF NEW YORK.

ELECTRIC SWITCH.

Application filed March 2, 1923. Serial No. 622,376.

To all whom it may concern:

Be it known that I, HERMAN J. H. HUBER, a citizen of the United States, residing at Schenectady, county of Schenectady, State 6 of New York, have invented certain new and useful Improvements in Electric Switches, of which the following is a specification.

My invention relates to electric switches 10 of the oil break type in which the final break occurs between contacts arranged in an explosion chamber, such switches being the form usually employed to control high potential circuits.

15 An object of my invention is to provide a switch structure which shall be adapted to be readily assembled, to have its parts adjusted to obtain the proper alinement, and to be firmly secured together against accidental displacement.

Another object is to provide a construction in which the fixed contact member of the switch may be adjusted and inspected conveniently and without the necessity of 25 first tearing down portions comprising the explosion chamber.

My invention will be better understood by reference to the accompanying specification and drawings and its scope will be 30 pointed out in the appended claims.

Figure 1 is a perspective view of the switch mechanism and the supporting means therefor, and

Fig. 2 is a vertical sectional view, drawn 35 to a larger scale, through a portion of the switch mechanism and its support.

Referring to Fig. 1 of the drawings, 1 represents the cover of an oil pot, not shown, in which the switch mechanism is 40 contained. Insulator bushings 2, 2 pass through and are secured intermediate their length to the cover 1 and preferably inclined in the manner illustrated. To the lower ends of the insulator bushings are ad- 45 justably secured, in the manner to be hereinafter described, adapters 3 which serve to carry the main stationary contacts 4 of the switch, the explosion chambers and the auxiliary fixed contacts which are mounted 50 with explosion chambers. The two adapters are firmly secured together in the proper spaced relation by bars 5. An insulating tube 6, only one of which is shown in Fig. 1, is slipped over each adapter. Movable 55 main switch members 7, 7 are mounted to

have a slight pivotal movement on an operating rod 8 which extends up out of the cover and is adapted to be raised or lowered by suitable mechanism, not shown, for respectively closing and opening the switch. 60 The lower end of the rod 8 carries a cross head 9 to each end of which is secured a block 10 by bolts 11. Each block carries a rod 12 constituting the movable member of the auxiliary or explosion chamber 65 switch and the blocks themselves are mounted to be adjusted toward or from each other by providing them with slots through which pass the bolts 11. The inner ends of the blocks 10 have downwardly projecting lugs 70 which are joined together in good electrical connection by straps 13.

Referring now to Fig. 2 showing the lower end of the insulator bushing 2 and the conductor rod 15 passing through it, it will 75 be seen that the adapter 3 is secured to the insulator bushing 2 through the instrumentality of a washer 16. This washer is clamped to the lower end of the bushing by a nut 17 threaded on the conductor rod 80 15, suitable friction washers 18 being provided between the bushing and the washer 16. The adapter 3 has its upper end inclined and provided with an annular flange 19 whose upper face abuts a flange 20 on 85 the washer 16. The inner edge of the flange 19 and the opposed portion of the washer 16 are beveled as shown to form a substantially V-shaped annular groove and seated in this groove is a transversely split 90 ring 21 having beveled surfaces corresponding to those of the flange 19 and washer 16. Bolts 22 extending through openings provided for that purpose in the flange 20 are threaded into the ring 21 and by tightening 95 these bolts the adapter may be firmly secured to the insulator bushing in any desired position of adjustment. Thus, should it be found that through some irregularity 100 of construction or mounting of the insulator bushing there existed a deviation in the angle made by the bushing from that necessary for the vertical positioning of the fixed explosion chamber contacts or the proper alinement of the main stationary contacts, 105 the adapter may be rotated slightly relatively to the bottom washer and, when in the proper position, secured thereto by tightening the bolts 10.

The lower or base portion of the adapter 110

3 has a central threaded opening and a laterally extending flange 23 against which is clamped a similar flange 24 of a receptacle 25 forming an explosion chamber. 5 Plate 26 supported from the receptacle 25 carries the external insulation tube 6 secured to it by fiber screws 28 and has a guide tube 29 for the contact rod 12 threaded into it at its central portion. A bottom 10 plate 30 of insulation is also threaded on the tube 29. A contact retainer 31 has a lower screw threaded portion 18 engaging in the aforementioned threaded opening in the adapter 3 to which it is secured in any 15 desired position of vertical adjustment by a lock nut 32. The adapter is preferably so constructed that the center line of the contact container 31 intersects the center line of the rod and bushing in the plane of the 20 lower end face of the bushing. The fixed contact of the explosion chamber or auxiliary switch comprises two members 33 and 34 each preferably formed in segments which are resiliently held together by garter 25 springs 35. The two members 33 and 34 rest one upon the other and are retained against vertical movement by a shoulder 36 on the inner surface of the container and by an annular member 37 secured to the container by screws 38. Conductors 39 provide a good electrical connection between the segments of the contact members and the retainer, the stationary contacts of the 30 main switch, being preferably attached to laterally projecting lugs 40, formed on the lower portion of the adapter. It should be noted that one side of the adapter, preferably the longer side, is cut away, thereby giving access to the contact container for the 35 purpose of adjustment or removal without the necessity of first removing the explosion chamber as has heretofore been necessary.

For obvious reasons it is desirable that all the switches controlling the same circuit should open at the same instant. Where variations are likely to occur in the sizes of parts, which is particularly true in the case of the length of the insulating bushings 2, it becomes necessary to raise or lower the contact holder 31 so that the times at which the breaks occur in a number of switches as well as the two breaks of the same switch may be made substantially the same. Adjustment of each auxiliary switch 50 fixed contact of the present switch is readily effected by loosening the lock nut 32 and then rotating the contact holder bodily to raise or lower the same as desired.

By the above described construction it will 60 be seen that I have provided a structure which may be readily attached to the lower end of a supporting bushing and wherein the stationary contact member may be adjusted to a vertical position by a rotative 65 adjustment of the adapter relative to the

bushing in the event that the bushing does not make the proper angle. The position of the stationary contact member may furthermore be readily adjusted vertically without first removing the explosion chamber so that all switches of the same set may be made to break at the same instant. Inasmuch as the movable members or rods 12 are mounted on the cross head 9 to provide for a limited lateral adjustment it is unnecessary to make provision for the lateral adjustment of the stationary contacts which cooperate therewith.

While I have described only one embodiment of my invention, I do not wish to be limited to the particular form shown and described as it will be apparent that many modifications therein may be made without departing from the scope of my invention as set forth in the appended claims.

What I claim as new and desire to secure by Letters Patent of the United States, is,—

1. In an electric switch device, the combination of a supporting member, a fixed contact, an adapter for supporting said fixed contact and means for securing said adapter to said member in various positions of angular adjustment.

2. In an electric switch device, the combination of an inclined supporting member, a washer secured thereto, a fixed contact, an adapter adjustable on said washer for supporting said fixed contact, and means for clamping said adapter to said washer in adjusted position.

3. In an electric switch device, the combination of a supporting insulator bushing, an annular member at the end thereof, means for rigidly securing said member to said bushing, a fixed contact, an adapter for supporting said fixed contact in a substantially vertical position and means for clamping said adapter to said member in various positions of angular adjustment.

4. In an electric switch device, the combination of a depending insulator bushing having a conducting rod extending therethrough, a washer, means engaging said rod for clamping said washer to said bushing, a fixed contact, an adapter for supporting said fixed contact, said washer and said adapter having opposed annular surfaces and means engaging said opposed annular surfaces for clamping said parts together in various positions of angular adjustment.

5. In an electric switch device, the combination of an inclined depending insulator bushing having a conducting rod extending therethrough, a washer, means engaging said rod for clamping said washer to said bushing, a fixed contact, an adapter for supporting said fixed contact in a substantially vertical position, said washer and said adapter being in engagement with each other and being provided with opposed annular

inclined surfaces, a ring having a pair of corresponding surfaces and means for drawing said ring into wedging engagement with said washer and said adapter to clamp said members together in any desired position of angular adjustment.

6. In an electric switch device, the combination of an inclined depending insulator bushing having a conducting rod extending therethrough, a washer, a nut on said rod for clamping said washer to the end of said bushing, a fixed contact, an adapter for supporting said fixed contact, said adapter having an annular flange engaging the under side of said washer, said washer and said adapter having opposed inclined annular surfaces forming a wedge shaped opening, a split ring in said opening having correspondingly inclined surfaces and a series of bolts extending through said washer and said ring for drawing up the ring into wedging engagement and thereby clamping the adapter to the washer.

7. In an electric switch device, the combination of an insulator bushing, an adapter carried thereby, a contact retainer and means for adjustably securing said contact retainer to said adapter.

8. In an electric switch device, the combination of an insulator bushing, an adapter carried thereby having an open side, and a contact retainer mounted in said adapter to have vertical adjustment therein.

9. In an electric switch device, the combination of an insulator bushing, an adapter carried thereby, and a contact retainer threaded into said adapter and extending

into the interior thereof, said adapter having an open side for rendering said retainer accessible.

10. In an electric switch device, the combination of an insulator bushing, an adapter secured to the lower end thereof having a base portion provided with a central threaded opening, a contact retainer threaded into said opening, stationary switch contacts carried thereby, a lock nut on the threaded portion of said retainer above the base portion of said adapter, and an explosion chamber secured to the under side of said adapter, said contact retainer extending up into said adapter and said adapter having one side portion cut away whereby the lock nut and the contact retainer are rendered accessible without the removal of the explosion chamber.

11. An electric switch comprising an explosion chamber, a movable contact projecting up through the bottom thereof, a fixed contact in the top of said chamber and means extending above the chamber for effecting vertical adjustment of said fixed contact.

12. An electric switch comprising an explosion chamber, a movable contact projecting up through the bottom thereof, a fixed contact, and a retainer for said contact threaded into and extending above the top of said chamber, whereby the position of said contact may be adjusted vertically from without the chamber.

In witness whereof, I have hereunto set my hand this first day of March, 1923.

HERMAN J. H. HUBER.

DISCLAIMER.

1,546,173.—*Herman J. H. Huber, Schenectady, N. Y. ELECTRIC SWITCH. Patent dated July 14, 1925. Disclaimer filed March 3, 1926, by the assignee, General Electric Company.*

Hereby enters this disclaimer under the provisions of and for the purpose set forth in rule 181, to the following claims in said Letters Patent, to wit:

“1. In an electric switch device, the combination of a supporting member, a fixed contact, an adapter for supporting said fixed contact and means for securing said adapter to said member in various positions of angular adjustment.

“2. In an electric switch device, the combination of an inclined supporting member, a washer secured thereto, a fixed contact, an adapter adjustable on said washer for supporting said fixed contact, and means for clamping said adapter to said washer in adjusted position.

“3. In an electric switch device, the combination of a supporting insulator bushing, an annular member at the end thereof, means for rigidly securing said member to said bushing, a fixed contact, an adapter for supporting said fixed contact in a substantially vertical position and means for clamping said adapter to said member in various positions of angular adjustment.

“7. In an electric switch device, the combination of an insulator bushing, an adapter carried thereby, a contact retainer and means for adjustably securing said contact retainer to said adapter.”
